UNITED STATES PATENT OFFICE.

WILLIAM H. BUNCE, OF JERSEY CITY, NEW JERSEY, AND DWIGHT SLATE AND JAMES RODDA, OF HARTFORD, CONNECTICUT, ASSIGNEES TO CALVIN C. WOOLWORTH AND JNO. S. GRAHAM, OF NEW YORK, N. Y.

MACHINE FOR PACKAGING POSTAL-CARDS.

SPECIFICATION forming part of Letters Patent No. 404,773, dated June 4, 1889.

Application filed March 13, 1886. Renewed September 21, 1888. Serial No. 286,014. (No model.)

To all whom it may concern:

Be it known that we, WILLIAM H. BUNCE, of Jersey City, in the county of Hudson and State of New Jersey, DWIGHT SLATE, of Hartford, in the county of Hartford and State of Connecticut, and JAMES RODDA, also of said Hartford, have invented certain new and useful Improvements in Machines for Packaging Postal-Cards and the Like, of which the following is a full, clear, and exact description, whereby any one skilled in the art can make and use the same.

Our invention relates to that class of machines that have heretofore been used for making envelopes, postal-cards, paper-wrappers, and the like, and in the form herein described our machine relates particularly to a postal-card machine.

The object of our invention is to provide a machine that shall automatically arrange in packages of any predetermined number the articles, as postal-cards or envelopes, that may be made, printed, or otherwise operated upon by the machine, and then secure these packages with a wrapping-band of suitable material, and in the same machine provide for the automatic counting of individual articles or of the number of packages.

The within-described machine that embodies our improvements as a whole consists of a supporting-frame with several rotary shafts bearing intermeshing cog-wheels, and cams operating on levers and like parts that make up the automatic device for receiving the cards, for feeding the piles of cards to the banding mechanism, and also the several mechanisms for feeding, banding, pasting, and delivering the cards and packages supplied to the machine, and the several devices are so combined and arranged in one structure as to be capable of performing their respective functions in a measure independently of any co-operation, and the several parts and mechanisms are capable of adjustment with relation to the individual and also to the collective action of the several mechanisms.

Our improvements consist in the combination of the several parts making up the feeding mechanism, the banding mechanism,

the gumming mechanism, and in details of the combination and arrangement of the several parts making up these mechanisms, as more particularly hereinafter described, and pointed out in the claims. 55

Referring to the drawings, Figure 1 is a side view, in elevation, of a Kidder printing-press with our improved machine attached and connected thereto. Fig. 2 is a plan or top view, on an enlarged scale, of part of our improved machine, showing part of the feeding and banding mechanism. Fig. 3 is a rear view of the machine with parts cut away. Fig. 4 is a detail side view, in vertical section, of the machine on plane denoted by line $x x$ in Fig. 3 and showing the pocket-clearing levers in side view. Fig. 5 is a detail view, in vertical section, of the bed of the machine, showing the levers that lift the pocket-clearing devices. Fig. 6 is a side view of our card-machine as a whole. Fig. 7 is a detail view, on an enlarged scale, of the tape-guide and its supporting-arm. Fig. 8 is a detail top view of these latter parts. Fig. 9 is a detail view, in vertical section, through the tape-guide on plane $z z$ 75 of Fig. 7. Fig. 10 is a view in vertical longitudinal section of part of the frame of the machine on a plane near the roll of banding-tape, the tape-shears being omitted for the sake of clearness. Fig. 11 is a detail side view, 80 on an enlarged scale, of the grasping-pinchers of the banding mechanism. Fig. 12 is a detail front view, on an enlarged scale, of these pinchers. Fig. 13 is a detail plan view, on an enlarged scale, of the tape-shears and connected 85 levers. Fig. 14 is a detail front view of part of the frame of the machine, showing the shears in rear view and the shear-operating cams and levers, and also part of the levers of the banding mechanism. Figs. 15, 16, 17, and 18 are detail views, on an enlarged scale, of the banding and gumming devices in several positions. Fig. 19 is a detail view, on an enlarged scale, of the clamp on the main driving-shaft. Fig. 20. 90 is a detail view, in cross-section, through this shaft on plane $x x$ of Fig. 19. 95

The machine now about to be described, and to which our said improvement is appurtenant, is a machine for making postal-cards. The machine is applicable to any other analog- 100

gous purpose. The paper-stock is, to begin with, upon a roll, and is of a width sufficient for making a number of postal-cards. It is fed into and through the printing-press in the 5 form of a continuous sheet, and is by such press properly printed with the postal-card emblems. The printing-press shown in the accompanying drawings is a so-called "Kidder" press. After the paper is printed it is, 10 as it moves along, slitted lengthwise, and after such lengthwise slitting it is, by a reciprocating knife, divided into lengths, and the divided parts are postal-cards proper. These postal-cards drop into pockets, and 15 after a predetermined number of them have been deposited in a pocket they are moved forward out of the pockets and into the grasp of a lateral feeding device, which by a step-by-step movement feeds the packages laterally. Each package as it comes to the proper 20 point in the lateral feeding is bound with a paper tape, the ends of which are pasted together. After this the package of postal-cards thus bound with a paper tape are by a continuation 25 of said lateral feeding fed off the end of a table into a proper receptacle. Meanwhile the register counts the packages.

In the accompanying drawings the letter *a* denotes the paper-stock whereof the postal-cards 30 are made. This paper-stock is fed through the printing-press and meanwhile printed with the proper emblems and legends of a postal-card. This wide band of paper-stock is slitted lengthwise (after being 35 printed) by means of rotary cutters, and the slitted sections of this paper-stock are divided into proper lengths for postal-cards by a reciprocating knife, and when the pieces pass through the reciprocating knife and drop down 40 from it they are postal-cards proper, properly printed and of the proper size. They drop into the pockets *d*. When the desired number of postal-cards have dropped into each 45 of these pockets, (in the present case twenty-five cards,) the pocket-clearing device operates, pushing the postal-cards out of these pockets and into the grasp of the lateral feeding device.

The pocket-clearing mechanism.—The letter *E* denotes the pocket-clearing mechanism as a whole. *e* denotes the clearing-lever, the upper end of which is furnished with fingers *e'*, one for each of said pockets, which fingers come in contact with and move the postal-cards out of the pockets *d*, the bottoms or 55 floors of the pockets being slotted longitudinally for the travel of such fingers. The lower end of the lever *e* is broadened and jointed on each side to the arms *f f'*, which 60 are clamped at their opposite ends to the rock-shaft *f²*, that is pivoted in bearings on the bed of the frame *A* of the machine. This connection of the lever *e* and the arms *f f'* is to enable the said fingers to have the necessary up-and-down motion that forms a part 65 of the motions made by the fingers *e'* in clearing the pockets, and this up-and-down mo-

tion is given by cam *g*, fast to the shaft *h* and bearing against friction-roll on pin *f³* on the upper end of the lever *f⁴*, which is pivoted to the rock-shaft at its lower end and connected to an upright branch *f⁵* by a bolt passing through slotted openings in the parts, which means of connection permits adjustment of the upper end of the lever *f⁴* toward or from the shaft *h*. The proper back-and-forth vibration of the said fingers *e'* at the upper end is given by the cam *g'*, also fast to shaft *h* and co-operating with a roll on the adjustable pin *e²* on the lever *e*. (Shown in Fig. 4 of the drawings.) The friction-rollers on lever *e* and lever *f⁴* are kept in contact with the bearing-faces of the cams by the yielding pull forward and downward of the diagonal spring *i*. The shaft *h* is so timed in its revolutions relative to the movements of the reciprocating knife *c* that the fingers of the pocket-clearing device, starting from the position shown in Fig. 4 of the drawings, move the postal-cards forward out of the 90 pockets *d* after twenty-five cards have been deposited in each pocket; and the movement of said fingers is, first, forward, carrying the cards out of the pockets; second, downward, dropping below the cards; third, backward, 95 and, fourth, upward again into position to again move the next lot out of the pockets.

The reciprocating knife *c* is provided with spring-fingers—one for each pocket—which, when the knife moves down, bear with a yielding pressure upon the postal-cards and hold them securely in the proper place during the operation of cutting. The packages of cards, when moved out of the pockets *d*, are given into the keeping of the lateral feeding mechanism.

The letters *n*, Fig. 2, denote arms, all clamped to the pivot-shaft *o*, that is supported in bearings on the back edge of the table *A'*, so that the free ends of these arms can rise and fall, and until the cards are moved into the keeping of the lateral feeding device the free ends of these arms *n* lie by gravity (of course a spring might be used) on the table *A'*. The arms *n* may all be connected together by a rod or bar *o'*, extending parallel with the shaft *o*. When a lot of postal-cards is moved forward out of the pockets *d*, it is moved into pocket-spaces *P* between two of these arms *n*. At the right time the arms *n* all move laterally to the left the distance of one pocket-space, carrying all the lots of postal-cards one remove to the left. Then the free ends of the arms *n* rise so as to be disengaged from the postal-cards, move backward one remove to the right, and drop down where they were at first. The movements of the shaft *o* and arms *n* to right and left are given by the rotary cam *r*, (see Fig. 3,) acting through the lever *s*, the spring *t* holding the friction-roll on the end of the arm *s'* of the lever *s* in proper contact with the cam *r*. The up and down motions of the arms *n* are given by the cam *u* on shaft *h* through the

medium of the lever v and connecting-rod w , that has on its top the slide-bearing z , acting against the bar o^4 , which connects the several arms n together.

- 5 It will be readily understood that as the lateral feeding device continues to operate the packets of postal-cards come successively one after another to be at the left of that arm n which is farthest left in the series.
- 10 From such position the packets are removed one by one still farther to the left, and there held stationary and bound with a paper tape. A part of this last movement is given by the usual leftward movement of the lateral feeding device, and an additional part is given by a supplemental feed device D.

15 The letter a' denotes a pusher hung on the pusher-rod b' , which rod reciprocates at proper times in its bearings in the arms n , and is held in normal position by the spring c' . As the lateral feeding device is moved, in the manner already described, toward the left, the lever d' at a proper time strikes the stop b , and the opposite end of this lever, bearing against a collar b^2 , (which is on the pusher-rod,) gives the pusher a' an additional and independent impulse of its own upon the packet of postal-cards, moving it to the place where it is bound with the paper

20 tape.

25 The binding mechanism.—The binding-tape is preferably a paper tape, is denoted by the letter g^2 , is wound in the form of a roll which is on the non-rotary shaft h' , and is held steady in position by cheeks $i' i''$, which are also non-rotary, and one of them is made removable for the purpose of permitting the insertion in place of a new roll of paper tape. The shaft and cheeks just referred to are 30 made non-rotary, as just described, that they may have a frictional contact with the roll of binding-tape and assist in keeping it from unwinding with undue and hurtful rapidity. The letter j' denotes a pivoted friction-pawl, the free end of which lies by gravity in contact with the periphery of the roll of tape, and also assists in keeping that roll from unwinding with undue speed. The tape is drawn from the roll, already described, down 35 through the guide k' , which is provided with the spring l' , that bears against the tape, to the end that it shall not be pulled through this guide any faster than the uses of the device below require. After the laterally-feeding device, acting in conjunction with the pusher a' , has fed one of the packs of cards into the position where it is to be bound with the tape, such pack is then to the leftward of the vertical plane of the guide k' . At this 40 point the ends of a pair of pinchers rise through a hole in the table, grasp the end of the tape just below the guide k' , and, retreating below the table, carry the end of the tape with them, drawing out past the guide k' a sufficient length of the tape for winding the succeeding package of cards.

45 The letters $m' m'$ denote the two levers of

the grasping-pinchers. (See Figs. 10, 11, and 12.) Each is pivotally hung upon a slide n' , having vertical reciprocation in the ways o' . A link p' is pivotally attached at one end to a projection from the slide n' , and it is pivotally attached at the other end to a connecting-rod r' , the lower end of which rod is pivotally attached to the pivoted lever s^2 , which bears upon its side a friction-roll co-operating with the rotary cam t' , held to contact therewith by the spring u' . As this cam, just mentioned, rotates, the lever s^2 rises and falls, and, through the medium of the connecting-rod r' , gives the grasping-pinchers their requisite up-and-down movement. The link p' has in its operation of the connecting-rod r' an independent up-and-down movement of its own between the two stop-pins $v' v'$, projecting from one of the grasping-pinchers m' , and this is for use in connection with the opening and shutting of the grasping-pinchers. The lower ends of the grasping-pinchers are formed into the cams w' , and a tappet-pin z' , borne in the link p' , co-operates with these cam-surfaces w' . When the grasping-pinchers are at the uppermost limit of their vertical play, they are open. When the connecting-rod r' begins its downward movement, it has the said independent play of its own between the stop-pins $v' v'$, and during this independent play it brings the tappet-pin z' into contact with the cam-surfaces w' , and thereby closes the grasping-pinchers upon the paper tape. This grasping of the pinchers upon the paper tape is continued until the grasping-pinchers are at the lowermost limit of their vertical play and until the connecting-rod r' begins its upward movement, in the first part of which the tappet-pin z' removes its pressure from the cam-surfaces w' and the spring a^2 opens the grasping-pinchers and holds them open until they are again closed for the purpose of grasping a fresh end of the tape. The spring b' , running from the slide n' to the connecting-rod r' , aids in making certain the proper independent vibratory motion of the link p' . After the grasping-pinchers have reached the downward limit of their vertical play, and thereby drawn down through the guide k' a sufficient length of tape for binding a pack of cards, the tape is severed just beneath the guide k' by shears, the levers of which are denoted by the letters $c^2 c^2$, Figs. 2, 13, and 14, and are pivoted on a pivot-pin d^4 and made to close for cutting purposes when properly permitted by the spring c^3 . These shear-levers are held apart until a cutting action is desired by the rotary pin-cam f^7 , the proper rotary vibration of which is given by the cam g^4 , acting through the lever h^2 and the connecting-rod i^2 , the lever h^2 being held to proper contact with the cam g^4 by the spring j^2 . This feeding of the end of the tape down through the table in sufficient lengths for binding a pack of cards takes place before the packet of cards to be bound thereby is

fed to the leftward of the guide k' by the supplemental feed device. When the pack of cards which is next to be bound is fed from right of the guide k' to left of the guide k' , it 5 carries with it and doubles upon itself the length of tape which has just been fed and cut off from the main roll for that purpose. (See Figs. 15, 16, 17, and 18.)

Contact with the table folds the tape against 10 the under side of the package, while contact with the vibrating finger k^2 correspondingly folds the tape upon the upper side of the package. The retaining-finger, just referred to, consists of a lever k^2 , pivoted in the frame, 15 and in this instance upon the standard bearing the roll of binding-tape at k^3 . A spring o^2 , connected with the standard and at that end of the lever k^2 opposite the package-retaining end, serves to hold said retaining or 20 folding end against the package. An arm k^4 , fast on the end of a rock-shaft l^2 , having a vibratory motion imparted to it by means of the rotary cam m^2 through the lever M gives the proper movements to said retaining-finger. 25 This retaining-finger is generally down. When a pack of cards in its leftward feed comes under the point of this retaining-finger, it is temporarily raised, that the pack may get under such point, when the finger again 30 drops and remains dropped until another pack is to be entered under its point. How the upper end of the severed length of tape is folded down upon the top of the pack of cards by the retaining-finger k^2 has been already 35 described, and how the lower part of the length of severed tape is folded against the under side of the pack of cards by contact with the table as the pack is fed to the leftward.

40 The operations and means by which the free extremity of the lower end of the length of severed tape is brought up on the side of the pack of cards, gummed, and pressed down to contact with what was the upper end of the 45 severed length of tape are as follows:

The letter p^2 denotes a folding-finger, which underlies the free extremity of the lower end of the tape after the tape is severed from the roll and has been partly folded about the 50 package. (See Fig. 15.) This folding-finger rises at the proper time and carries the free end of the tape last mentioned upward along the side of the pack of cards, both it and said free end of the tape projecting above the top 55 of the pack of cards. The necessary vertical movement of this folding-finger is given by the rotary cam r^2 acting in conjunction with the lever t^2 , (held to contact with the cam by spring u^2), which lever t^2 carries the folding-finger. 60 When the folding-finger is near the upper limit of its vertical play, it stands vertically projecting above the top of the pack of cards, and between it and the pack is the free end of what was the lower part of the 65 severed tape, (see Fig. 16,) also extending vertically above the top of the pack of cards. Now this upwardly-extending end of the pa-

per tape is gummed by a device shortly to be described, after which the folding-finger turns down flat upon the top of the pack of cards 70 and presses this gummed end of the tape upon the upper surface of the other end of the tape, uniting the two firmly and permanently through the agency of the gum or mucilage. The folding-finger p^2 is pivotally hung in or 75 upon (a piece attached to) the lever l^2 , and the spring v^2 constantly tends to turn the folding-finger down flat upon the top of the pack of cards, as described, and for the purpose described, and just as soon as the folding-finger rises high enough in its vertical play so that its joint is above the level of the top of the pack of cards this spring v^2 turns it flat down upon the top of the pack of cards, and in so doing gums the ends of the tape together, as already described. While the folding-finger is lying flat upon the top of the pack of cards and pressing the gummed end of the tape into contact with the other end a presser-lever w^2 comes down upon the top 85 of the folding-finger (see Fig. 17) with a considerable pressure for the purpose of effectuating the contact between the gummed end of the tape and the ungummed end. This presser-lever is operated by the cam z^2 through 90 the medium of the lever a^3 , connecting-rod a^4 , and arm a^5 , the latter being fast to the same shaft a^6 that bears on its opposite end the presser-lever w^2 . (See Fig. 14.)

The gumming device.—The letter d^3 denotes a reservoir of mucilage, into which the lower end of the wiper e^3 descends (see Fig. 16) at the proper time, and as it rises it carries on its free end a little of the mucilage. As it rises, the pivoted gummer b^3 , extending 100 at this time substantially horizontally, moves laterally, meets the free end of the wiper e^3 , takes from it by contact (see Fig. 15) a little of the mucilage, retreats backward laterally, and then, turning down rotarily, comes in 110 contact with the end of the tape, (see Fig. 16,) which at the time is extending upward vertically alongside the folding-finger p^2 , and deposits thereon a little of the mucilage, after which it turns upward rotarily to what may 115 be called its "normal" position. The gummer b^3 is pivoted on an arm on the rock-shaft g^3 , which rock-shaft is held backward in what may be called its "normal" position by the spring h^3 , but carries the gummer b^3 to meet 120 the wiper e^3 through the impulsion of a rod i^3 , attached to and carried by the laterally-feeding device, (the device which feeds the packs of postal-cards laterally step by step, already described.) The motion of the rock-shaft g^3 , which is given by the rod i^3 and spring h^3 , gives the wiper e^3 its rotary vibratory movement, already described, through the medium of the connecting-rod j^3 and the arm k^3 , which is fast on the wiper. The 125 rotary movements of the gummer b^3 , already described, are given by the up and down movements of the presser-lever w^2 through the medium of the arm l^3 (pivoted on presser-

lever w^2 and acted upon by spring m^3) and the connecting-rod n^3 . The spring o^3 gives a yielding contact between the gummer b^3 and the wiper e^3 . As the revolutions of the main 5 shaft and the several cam-shafts connected therewith by means of the intermeshing cog-wheels continue, the several parts of the mechanisms are moved, so that the package C of cards that has been banded is released 10 from the grasp of the presser-finger and of the presser, and is free to be thrust along by the forward feed of the succeeding package.

In order that the folding-finger may be withdrawn from contact with the band and 15 carried to its position below the table without dragging on or loosening the band, the base of the finger is first lifted from contact with it and drawn slightly backward before the downward movement begins. This is an im- 20 portant feature of our invention, and is accomplished by the following mechanism:

The bent lever t^2 is pivotally connected at its upper end to a second lever t^3 , that is pivoted to a lug t^4 on the frame at a point on the 25 lever between this pivotal connection with lever t^2 and the end bearing against the cam r^3 , (see Fig. 10,) and the movement of the folding-finger is the resultant of the separate and of the combined movements of levers t^2 and t^3 . 30 as produced by the irregular surfaces on the cams r^2 and r^3 , respectively. To produce the peculiar lifting of the folding-finger, the pin on the lower end of lever t^2 drops into a hollow on the cam r^2 , which allows the forward 35 end of the arm of lever t^3 to swing upward under the pull of a spring u^2 . The other cam r^3 then acts on the lever t^3 and moves the forward end of the lever t^2 forward (*i. e.*, to the right in Fig. 10) and slightly downward, and 40 during this operation of the lever t^3 the cam r^2 begins to act on the pin in the lever t^2 , causing the forward end of the said lever to continue its downward movement, dragging the finger across the edge of the package of cards 45 and side of the hole and opening it to its vertical position, in which it is held by contact with such side until the next band is to be folded. After the packs of cards are bound with the tape in the manner already described 50 they continue to feed to the leftward by the pressure of each pack upon its fellow to its left until they drop off the left end of the table into a proper receptacle.

The letter p^3 denotes a rotary shaft carrying the five cams last referred to, which makes one complete rotation with the binding and delivery of each pack of cards. This shaft, through a crank and connecting-rod, operates the register or counting device K, which counts 60 or registers the number of packs of cards printed, bound, and delivered. This register is not our invention, and any suitable register can be used for this purpose.

The cog-wheel B on the main driving-shaft 65 B' of our machine is loose on the shaft, except when secured to it by the sliding body part of the positive clutch B², (see Figs. 2, 19,

and 20,) that is halved onto the hub of the wheel B, which is in mesh with a cog-wheel of the printing-press. (See Fig. 1.) When the 70 printing-press and the card-machine have been once adjusted and timed so that the several stops are properly taken in printing, feeding, banding, and counting, they may be disconnected and proofs struck off or changes 75 made in the press and the two machines again connected without disturbing the adjustment.

We claim as our improvement—

1. In combination, the pockets d and the pocket-clearing device E, having the forward, 80 downward, backward, and upward motions, all substantially as described, and for the purpose set forth.

2. The lateral feeding device composed of pivoted arms n , having the leftward, upward, 85 rightward, and downward motions, as described, in combination with the independent pusher a' , actuated by lever d' and stop b , all substantially as described, and for the purpose set forth. 90

3. The pivotally-hung and vertically-reciprocating folding-finger p^2 , in combination with its actuating-spring v^2 , substantially as described, and for the purpose set forth.

4. In combination with the pivotally-hung 95 and vertically-reciprocating folding-finger p^2 , the reciprocating presser-lever w^2 , all substantially as described, and for the purpose set forth.

5. In combination, pockets d , clearing device e , lateral feeding device n , pusher a' , tape-guide k' , grasping-pinchers $m' m'$, and shears $c^2 c^2$, all substantially as described, and for the purpose set forth. 100

6. In combination, in a machine of the 105 within-described class, a receiving-pocket with slotted bottom, the pocket-clearing lever, and the mechanism, substantially as described, whereby the said pocket-clearing lever is given an intermittent reciprocation 110 along the pocket alternately in and out of it, all substantially as described.

7. In combination with package-holding mechanism, substantially as set forth, the lever bearing the folding-finger and pivotally 115 supported on a second lever, and the mechanism whereby the folding-finger is lifted from the end of the tape after it has been gummed and the package bound, all substantially as described. 120

8. The herein-described tape-feed mechanism, comprising a pair of pinchers consisting of levers $m' m'$, pivoted upon a reciprocating slide, the said levers being provided with cam-surfaces w' , pins v' , and a spring to hold the 125 clamping ends separated when they advance to feed the tape, combined with the actuating-rod r' and links p' , carrying the pin z' , said links connecting the said rod and slide n' and operating the pincher-levers, as set 130 forth.

9. The combination, with the pusher a' and the tilting folding-finger k^2 , for doubling one end of the paper tape upon the package, of the

mechanism for folding the other end upon the package, consisting of the pivotally-hung vertically-reciprocating folding-finger p^2 and its actuating-spring, substantially as described.

10. In a machine of the class described, the combination of the pockets d , pocket-clearing devices, substantially as set forth, and the lateral feeding device composed of pivoted arms n , having the leftward, upward, rightward, and downward motions, substantially as described, and for the purpose set forth.

11. In a machine of the class described, the combination of the pockets d , pocket-clearing devices, substantially as described, the lateral feeding device composed of pivoted arms n , having the four motions set forth, and the independent pusher a' , actuated by lever d' and stop b , as explained.

12. In a machine of the class described, the combination, with banding mechanism, substantially as herein described, in which the banding-tape is fed across the path of movement of the package of cards, of feeding mechanism, consisting of means, substantially as described, for imparting to a package of cards a main progressive movement, and a

pusher a' , for imparting a supplementary movement to the package to move it into the place where it is bound with the tape, substantially as set forth.

13. In a machine of the class described, the combination, with the folding-finger p^2 , pivotally hung to a lever t^2 , and a lever t^3 , pivoted to said lever t^2 and to the machine, of cams r^2 and r^3 , substantially as shown, to operate the said levers in the manner described, whereby after the folding-finger has been operated to fold the tape upon a package its base is first lifted from contact with it and the finger drawn slightly backward before its downward movement begins, for the purpose set forth.
